UNITED STATES PATENT OFFICE.

ORLAND D. ORVIS, OF NEW YORK, N. Y.

STEAM-BOILER FURNACE.

1,071,787.

Specification of Letters Patent. Patented Sept. 2, 1913.

Application filed January 20, 1911. Serial No. 603,685.

To all whom it may concern:

Be it known that I, ORLAND D. ORVIS, a citizen of the United States, residing in the city of New York, borough of Manhattan, 5 county and State of New York, have invented a certain new and useful Steam-Boiler Furnace, of which the following is a specification.

This invention is a steam boiler furnace, 10 the same being adapted, more particularly, for water tube boilers.

The invention embodies a plurality of baffles supported on the circulating tubes of the boiler, said baffles lying over the grate 15 chamber and being spaced relative to each other so as to produce an opening for the escape of the products of combustion, and means independent of said baffles for feeding steam and air directly into the grate 20 chamber and below the baffles therein, the steam and air being fed in thin sheets substantially throughout the area of the grate chamber, whereby the sheets of steam and air are mixed directly with the volatile 25 products of combustion for the purposes, mainly, of consuming the carbon in the smoke and to increase the combustion of the gases arising from the bed of fuel resting upon the grate.

30 In the accompanying drawings, I have illustrated one practical embodiment of the invention, but the construction shown therein is to be understood as illustrative, only, and not as defining the limits of the invention.

Figure 1 is a vertical longitudinal section partly in elevation. Fig. 2 is a plan view, partly in section, on an enlarged scale, the plane of the section being indicated by the 40 dotted line 2-2 of Fig. 1, the blast pipes H I being shown in plan.

In order that others skilled in the art may understand my invention, I have illustrated it in connection with an ordinary 45 water tube boiler, wherein—

A designates the inclined circular tubes, B the grate chamber provided with any suitable grate b, C the front wall provided with fuel door, c, and an ash pit door, 50 c', D the bridge wall at the rear of the grate chamber, E the vertical partitions co-operating with the inclined tubes, F the steam drum and G a suitable outlet for the waste gases and products of combustion. 55 All these parts and various other details

may be of the usual or any preferred construction.

H designates a horizontal blast pipe which is embedded in front wall, C, of the furnace, said front wall being constructed 60 to provide blast outlets, h. The blast pipe is provided with a series of nozzles, H', which extend into openings, h, of the front wall for the purpose of discharging streams of steam and air directly into the grate 65 chamber. Bridge wall, D, is constructed to provide a series of blast outlets, d, and embedded within said bridge wall is another blast pipe, I, the same being provided with nozzles, I', which are positioned to 70 discharge streams of steam and air directly into the grate chamber. Blast pipes, H, I terminate at one end in the walls of the furnace, the other ends of said blast pipes being extended beyond the other side wall 75 of said furnace. The extended ends of blast pipes, H, I are provided with fittings, J, J', respectively, each fitting being preferably of the form shown more particularly in Fig. 2. Attached to each fitting is an 80 air inlet pipe, K, the same extending in any suitable direction with respect to the furnace. Each inlet pipe is attached at one end to a fitting so as to communicate therewith, but at the other end of each air inlet 85 pipe is provided a muller, k, which may be of any suitable construction.

L is a steam supply pipe extending outside of the furnace, preferably, between fittings, J, J'. Said pipe is provided with 90 nozzles, L', extending into fittings, J, J', each of said nozzles extending across the delivery end of the air inlet pipe, K, which is attached to the fitting, whereby a jet of steam admitted by the nozzle will induce 95 the inflow of air through pipe, K. A feed pipe, M, is connected to pipe, L intermediate the ends thereof, said supply pipe, L, being provided with a pet cock, m, for the purpose of draining off any water of condensation which may accumulate in pipe, L, or at the lower part of pipe, M. Either of the blast pipes, H or I, may be cut out of use by adjusting one of two valves, m', m², said valves being provided in pipe, L, at the 100 respective sides of feed pipe, M. By reference to Fig. 2 it will be seen that valve, m, may be operated to drain water of condensation from pipes, L and M. By closing valve, m', steam will not be admitted to blast 105 110

pipe, H, and by closing valve m^2 , the supply of steam will be cut off from blast pipe, I. The described construction enables steam to be supplied by pipe, M to blast 5 pipes, H, I when all the valves are opened, but by closing one or the other of valves, m' , m^2 , the supply of steam may be cut off separately from the respective blast pipes, H, I.

10 N, O designate baffles positioned in the upper part of the grate chamber, B, and above blast pipes, H, I. Each baffle is composed, preferably, of fire brick or fire clay tiles resting upon the lowermost row of 15 tubes, A, of the boiler, but the particular construction of the baffles and the means for supporting the same within the upper part of the grate chamber, may be modified as desired by a skilled constructor. For the 20 purpose of economy, however, and for the easy and quick installation of the baffles in existing furnaces, it is preferred to employ fire brick adapted to be placed upon boiler tubes so as to be supported thereby.

25 The baffles, N, O are spaced relatively to each other, baffle N being in the forward part of the grate chamber, and baffle O in the rearward part thereof. By spacing the baffles as described, an outlet, P is provided 30 centrally in the upper part of the grate chamber, whereby the smoke and products of combustion are free to escape in an upward direction so as to substantially envelop the forward portion of the nest of boiler 35 tubes, after which the products of combustion will sweep over the top of the first partition, E, and thence flow downwardly around the tubes and between the partitions, E, E and finally the products of combustion will flow 40 in an upward direction and in the rear of the second vertical partition, E, so as to make their escape through the outlet, G.

In the operation of the furnace, fuel is supplied to the grate chamber through door, 45 e, and steam is supplied by nozzles, L', to the fittings, J, J', respectively, so that the inflow of steam into pipes, H, I will induce the inflow of air through pipes, K, into said pipes, H, I, respectively. Steam and 50 air are thus supplied to pipes, H, I, and these pipes operate to distribute air in thin sheets into the grate chamber and below baffles, N, O therein. The nozzles of each blast pipe are so constructed as to 55 spread the streams of steam and air, the stream issuing from one nozzle being directed toward the right and left, as indicated by the intersecting lines in Fig. 2, and these streams from the nozzles of each 60 blast pipe are so diffused and distributed in the grate chamber as to produce a thin sheet of steam and air over the grate, b. The sheet of steam and air supplied by blast pipe, H, flows rearwardly from the front 65 wall, C, and into the grate chamber. Con-

trawise, the sheet of steam and air supplied by blast pipe, I, flows in a forward direction from bridge wall, D, and into the grate chamber, the two sheets of steam and air supplied by pipes, H, I, respectively, flowing in opposite directions into the grate chamber and from walls, C, D, respectively.

The two sheets of steam and air are injected into the grate chamber so as to flow toward each other, and so that the aggregate area of the two sheets will be equal substantially to the area of the grate, whereby the steam and the air will be injected into all parts of the volatile products of combustion arising from the grate, so that the steam and air are mixed intimately with the volatile products of combustion. The result of such injection of steam and air directly into the products of combustion is to thoroughly consume the carbon in the smoke and to increase combustion of the gases arising from the fuel. The ascending products of combustion resulting from the mixture of steam and air with the gases and smoke are not free to escape from all parts of the grate chamber, but they must flow below baffles, N, O, and finally emerge from the grate chamber through outlet, P, the area of which is less than that of the grate and approximately equal to that of the chimney, thereby accelerating, instead of retarding, the natural draft of the furnace. The currents (superheated steam and heated air) thus injected in the furnace are in the form of thin sheets, and they move 90 with increased velocity in the chamber, due to expansion of the air and steam within the heated pipes embedded in the furnace walls. The thin sheets or currents of steam and air are in close proximity to the burning fuel, and they become thoroughly mixed with the volatile gases so as to result in a 95 combustion of the gases which is believed to be as near to perfect combustion as is obtainable in furnaces of this type. The 100 area of the outlet, P, being less than that of the grate chamber, the ascending gases mixed with steam and air are baffled to some extent by baffles, N, O, thus resulting in a 105 circulation within the grate chamber and below the baffles, the effect of which is to 110 thoroughly burn the gases and consume the 115 carbon in the smoke.

While I have shown the front and bridge walls as provided with the blast pipes, it 120 is evident that said pipes may be installed in the side walls. Accordingly, it is desired to avail myself of the mere change in the position of the blast pipes, and in the claims I shall refer to said blast pipes 125 as being positioned in opposite walls.

Having thus fully described the invention, what I claim as new and desire to secure by Letters Patent is:—

1. In a furnace for water tube boilers, the 130

combination of the furnace walls forming a grate chamber, blast pipes in opposite walls of said chamber, baffles positioned in the upper part of the grate chamber, said baffles being separated with respect to each other and producing a throat substantially centrally of the grate chamber for the free escape of the gaseous products of combustion, and a plurality of series of blast nozzles attached to the blast pipe and with the nozzles of the two series positioned to direct steam and air in a common plane, said nozzles being provided with horizontally positioned flaring outlets operating to spread the outflowing current of steam and air horizontally and in thin sheets across the grate chamber and below the baffles, said blast nozzles of one pipe operating to direct one sheet of steam and air in one direction from one wall, and the blast nozzles of the opposite pipe operating to direct another sheet of steam and air in an opposite direction to the first named sheet, the currents flowing on diverging lines from the nozzles of each series to intersect with each other and the two oppositely projected sheets of steam and air meeting or intersecting with each other so as to result in an intimate admixture of the steam and air with the gaseous products of combustion.

2. In a furnace for water tube boilers, the combination with the furnace walls forming a grate chamber and nested water tubes extending across said chamber, of baffles

positioned over the grate chamber and 35 spaced with respect to each other to produce a throat or outlet substantially centrally of said chamber, said baffles consisting of firebrick which are imposed upon, and supported directly by, the lower tier 40 of said nested water tubes, blast pipes positioned in opposite walls of said grate chamber, means for supplying steam and air to said blast pipes, and a plurality of series of blast nozzles attached to said pipes 45 and positioned in facing relation for discharging steam and air in a common plane with reference to the grate chamber, said blast nozzles being provided with horizontally positioned flaring outlets which 50 operate to direct the outflowing currents of steam and air on diverging lines so that the individual streams will intersect one with the other, the two series of nozzles operating to project the steam and air in thin 55 sheets and opposite directions and in intersecting paths so that the aggregate area of the two sheets of steam and air is equal substantially to the area of the grate chamber.

60

In testimony whereof I have signed my name to this specification in the presence of two subscribing witnesses.

ORLAND D. ORVIS.
